United States Patent Office

Des. 226,330
Patented Feb. 13, 1973

226,330

CAMERA FLASH ATTACHMENT

Peter T. Quinn, Littleton, Colo., assignor to
Honeywell Inc., Minneapolis, Minn.

Continuation of design applications Ser. No. 18,974 and
Ser. No. 18,981, both Sept. 3, 1969. This application
June 5, 1970, Ser. No. 23,340

Term of patent 14 years

Int. Cl. D16—07

U.S. Cl. D61—1 F

FIG. 1

FIG. 2

FIG. 3

FIG. 4

FIG. 1 is a front perspective view of a camera flash attachment showing my new design;

FIG. 2 is a rear perspective view thereof;

FIG. 3 is a front perspective view of a second embodiment of my new design wherein an adjustment knob is located in the side of the lower part of the housing;

FIG. 4 is a rear perspective view of FIG. 3.

This application is a continuation of design patent applications Ser. Nos. D. 18,974 and D. 18,981, both filed Sept. 3, 1969.

I claim:

The ornamental design for a camera flash attachment, as shown and described.
